FIG. 1 is a front elevational view of a necklace made of woven beads showing my new design;

FIG. 2 is a side elevation view thereof;

FIG. 3 is an enlarged side elevational view of one of the tassels attached at the bottom of the necklace;

FIG. 4 is an elevational view of the opposite side of the portion indicated in FIG. 1;

FIG. 5 is an elevational view opposite the corresponding portion in FIG. 1;

FIG. 6 is an elevational view opposite the portion indicated in FIG. 1;

FIG. 7 is an elevational view of the portion indicated in FIG. 1 the unseen sides being a mirror image of those shown;

FIG. 8 is an elevational view opposite the portion indicated in FIG. 1; and

FIG. 9 is an elevational view opposite the portion indicated in FIG. 1.

FIGS. 4-9 are shown on an enlarged scale to better illustrate the pattern.

The drawing is lined for the colors black and grey.

When unfolded, the rear of the necklace is a mirror image of the front.

I claim:

The ornamental design for a necklace made of woven beads, as shown and described.
